(57) **CLAIM**

The ornamental design for a wallet, as shown and described.

DESCRIPTION

FIG. 1 is a front perspective view of a wallet showing my new design in a folded state;

FIG. 2 is another perspective view thereof, shown in an unfolded state;

FIG. 3 is an opposite side perspective view of the wallet shown in the unfolded state; and,

FIG. 4 is arear perspective view of the wallet shown in the folded state.

The dash-dash broken lines illustrate stitching and form part of the claimed design.

The dot-dash broken lines form no part of the claimed design. The blank white portions of the wallet within the dot-dash boundary line forms no part of the claimed design.

1 Claim, 4 Drawing Sheets
